US0D1071191S

(12) **United States Design Patent** (10) **Patent No.:** **US D1,071,191 S**
Chen (45) **Date of Patent:** **** Apr. 15, 2025**

(54) **CANISTER CAP**

(71) Applicant: **SUZHOU SINGMED MEDICAL DEVICE SCIENCE AND TECHNOLOGY LTD.**, Jiangsu (CN)

(72) Inventor: **Thomas Chen**, Jiangsu (CN)

(73) Assignee: **SUZHOU SINGMED MEDICAL DEVICE SCIENCE AND TECHNOLOGY LTD.**, Jiangsu (CN)

(**) Term: **15 Years**

(21) Appl. No.: **29/888,739**

(22) Filed: **Apr. 4, 2023**

(30) **Foreign Application Priority Data**

Oct. 14, 2022 (CN) 202230679200.X
(51) **LOC (15) Cl.** **24-02**
(52) **U.S. Cl.**
USPC **D24/127**; D24/130

(57) **CLAIM**

The ornamental design for a canister cap as shown and described.

DESCRIPTION

FIG. 1 is a front, top perspective view of a canister cap showing the new design;

FIG. 2 is a front, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 3 Drawing Sheets
